UNITED STATES PATENT OFFICE

FRANK E. WAKEFIELD, OF ELGIN, ILLINOIS, ASSIGNOR TO LUCIEN LELONG INC., OF CHICAGO, ILLINOIS, A CORPORATION OF ILLINOIS

DESIGN FOR A VANITY CASE OR SIMILAR ARTICLE

Application filed May 26, 1930. Serial No. 35,775. Term of patent 14 years.

To all whom it may concern:

Be it known that I, FRANK E. WAKEFIELD, a citizen of the United States, and a resident of the city of Elgin, in the county of Kane and State of Illinois, have invented a new, original, and ornamental Design for a Vanity Case or Similar Article, of which the following is the specification, reference being had to the accompanying drawings, forming a part hereof.

On the drawings:

I claim:

The ornamental design for a vanity case, or similar article, as shown.

FRANK E. WAKEFIELD.
